F. E. FIELD

AMPLIFIER CIRCUITS

Filed Dec. 1, 1922

Inventor:
Frank E. Field
by J. C. Palmer Atty

UNITED STATES PATENT OFFICE.

FRANK E. FIELD, OF SOMERVILLE, NEW JERSEY, ASSIGNOR TO WESTERN ELECTRIC COMPANY, INCORPORATED, OF NEW YORK, N. Y., A CORPORATION OF NEW YORK.

AMPLIFIER CIRCUITS.

Application filed December 1, 1922. Serial No. 604,154.

To all whom it may concern:

Be it known that I, FRANK E. FIELD, a citizen of the United States, residing at Somerville, in the county of Somerset, State of New Jersey, have invented certain new and useful Improvements in Amplifier Circuits, of which the following is a full, clear, concise, and exact description.

This invention relates to amplifier circuits having means for adjustment in their input circuit, and has for an object, to avoid singing due to electrostatic coupling between the output circuit and the input circuit.

A further object of the invention is to avoid disturbances due to the manual operation of a switch in an amplifier circuit.

In the form of the invention disclosed herein, a switch makes adjustable connection to taps on the secondary winding of the input transformer for adjusting the gain of the amplifier. Since the metallic mass of the switch is relatively large, its capacity to conductors in the output circuit is much larger than that of the lead wires in the input circuit. It has been found that if the switch is connected to the grounded cathode and the fixed terminal of the secondary winding connected to the grid by a short lead wire, the tendency of the circuit to sing is very greatly reduced. Disturbances due to accidental contact of the operator's hand with the metallic portions of the switch are also minimized.

The invention will be more fully understood from the following detailed description and claims taken with the accompanying drawing which shows schematically a vacuum tube amplifier circuit embodying the invention.

Referring to the drawings by reference numerals, the input transformer 5 impresses signals on the vacuum tube 7, and the amplified signals are impressed by a transformer 9 on a second amplifier stage, comprising vacuum tubes 11 and 12 in the so-called "push-pull" relation. Connection is made to any suitable work circuit by an output transformer 14.

The secondary winding of input transformer 5 is provided with taps 16 and connection is made to these taps by a switch 17 for adjusting the amplification. Switch 17 is connected to the cathode heating circuit which is grounded at 18. This insures that the switch 17 remains at the potential

of the grounded portions of the output circuit and reduces very greatly the electrostatic feed-back of energy from the output circuit to the input circuit. For the same reason the lead wire connecting the ungrounded terminal 20 of the secondary winding to the grid is made as short as possible.

While only a single form of the invention has been shown, it is to be understood that the invention may assume other forms within the scope of the appended claims.

The invention claimed is:

1. In combination, a source of incoming signal waves, a space discharge tube translating device supplied with said waves, said device having a cathode, anode and control electrode, an impedance connected effectively across said source, one end of said impedance being conductively connected to said control electrode by a short conductor, a plurality of taps on said impedance for adjusting the potential of said waves supplied to said device, and a switch conductively connected to said cathode and to ground, said switch having a contact adjustably engaging said taps.

2. In combination, a source of incoming signal waves, a space discharge tube translating device supplied with said waves, said device having a cathode, anode and control electrode, a transformer connected between said source and said device, the primary of said transformer being connected to said source, one end of the secondary of said transformer being conductively connected to said control electrode by a short conductor, a plurality of taps on said secondary of said transformer for adjusting the potential of said waves supplied to said device, and a switch conductively connected to said cathode and to ground, said switch having a contact adjustably engaging said taps.

3. An amplifier comprising a plurality of electron discharge devices connected in tandem, a portion of the output circuit of the last of said devices being grounded, potential adjusting means connected to the input conductors of a preceding discharge device, and a low impedance connection from said adjusting means to ground.

In witness whereof, I hereunto subscribe my name this 24th day of November, A. D., 1922.

FRANK E. FIELD.
